Primary Examiner — Jennifer L Watkins(74) *Attorney, Agent, or Firm* — Banner & Witcoff, Ltd.(57) **CLAIM**

The ornamental design for a bag, as shown and described.

DESCRIPTION

FIG. 1 is a top, front, left perspective view of a bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even-length broken lines within the shaded area represent stitching and a zipper track and form no part of the claim. All other broken lines depict portions of the article and form no part of the claim.

1 Claim, 4 Drawing Sheets# US D1,038,611 S
